HOLDER FOR CIGARETTE PACKAGES OR SIMILAR ARTICLES

William L. Soffe, Salt Lake City, Utah

Application July 10, 1950, Serial No. 11,052

Term of patent 14 years

(Cl. D85—2)

To all whom it may concern:

Be it known that I, William L. Soffe, a citizen of the United States, residing at Salt Lake City, in the county of Salt Lake and State of Utah, have invented a new, original, and ornamental Design for Holders for Cigarette Packages or Similar Articles, of which the following is a specification, reference being had to the accompanying drawing, forming part thereof.

Fig. 1 is a perspective view of a holder for cigarette packages or similar articles, showing my new design;

Fig. 2 is a perspective view of the holder, the cover being omitted;

Fig. 3 is a top view of the cover.

I claim:

The ornamental design for a holder for cigarette packages or similar articles, as shown.
